DISPLAY COOKER

Robert G. Wilson, 643 E. Faris Road,
Greenville, S.C. 29605

Filed Mar. 7, 1966, Ser. No. 1,299

Term of patent 14 years

(Cl. D81—10)

Fig. 1.

Fig. 2.

The side of the base not shown is flat and plain.

The dominant features of applicant's design are shown in full lines.

I claim:

The ornamental design for a display cooker, substantially as shown and described.
